(57) **CLAIM**

The ornamental design for a clamping device, as shown and described.

DESCRIPTION

FIG. 1 is a top, front, left perspective view of a clamping device showing my new design in a first position;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the clamping device form no part of the claimed design.
